Inventor:
Orlando R. Marsh
By Hill & Hill, Atty.

UNITED STATES PATENT OFFICE.

ORLANDO R. MARSH, OF CHICAGO, ILLINOIS.

PHONOGRAPH-REPRODUCER.

1,392,430.

Specification of Letters Patent. Patented Oct. 4, 1921.

Application filed December 9, 1918. Serial No. 265,890.

To all whom it may concern:

Be it known that I, ORLANDO R. MARSH, a citizen of the United States, residing at Chicago, in the county of Cook and State 5 of Illinois, have invented certain new and useful Improvements in Phonograph- 60 Reproducers, of which the following is a description.

My invention belongs to that general class 10 of devices employed with phonographs and devices of that character, to audibly reproduce from a record, the audible sounds which were employed in making up the record. It has for its object a device of the 15 character described which shall accomplish the purpose stated in a more satisfactory and effective manner than has been heretofore possible, and this in a simple device which may be economically constructed and 20 which possesses a very large degree of durability. To secure the full measure of the advantages secured by my invention, I so arrange and assemble the various parts as 25 to dispense with all pivot or knife edge connections or supports, which by use are liable to become loose and rattle, and also to dispense with all springs requiring adjustment.

To this end my invention consists in the 30 novel construction, arrangement and combination of parts herein shown and described, and more particularly pointed out in the claims.

In the drawings, wherein like reference 35 characters indicate like or corresponding parts,

Figure 1 is a face view of my improved device;

Fig. 2 is a rear view of the same device;

Fig. 3 is a section taken substantially on 40 line 3—3 of Fig. 1;

Fig. 4 is a section taken substantially on the line 4—4 of Fig. 1;

Fig. 5 is a plan view of the supporting 45 plate; and

Fig. 6 is a modification of the form shown in Fig. 5.

In the drawings, 1 indicates the frame of the reproducer provided with a removable back 2, and the usual diaphragm 3. The diaphragm is preferably maintained between cushions 4—4 in the well known manner and extends across the face of the frame as shown. The frame is provided with a 50 base 5 to which is secured a supporting plate 6 in such manner as to prevent free vibra- 55 tion to the edges of the plate. This supporting plate is of such material and so constructed as to permit a considerable degree of vibration in itself, and at the same time 60 of sufficient resiliency to permit the freest movement of the free end of stylus-bar 7 which it centrally supports. For this purpose I prefer to form the plate of such material, that while reliably supporting the 65 stylus-bar 7 it will permit the upper end of the same engaged with the diaphragm to reliably vibrate or oscillate in any direction. I have had very satisfactory results with 70 metal such as for example thin steel connected to the base at three points arranged in a triangular position. In other cases I have secured fair results with hard rubber or similar material for the plate similarly supported, and in still others I have employed a combination of both. In order to 75 secure the desired freedom of vibration of the free end of the stylus-bar, I prefer to reduce the area of the plate and to connect the same to the base 5 at certain points, thus 80 permitting free vibration of the edges of the plate between the points of support, which preferably consist of an odd number. As 85 shown in Fig. 5, the plate is supported at three points, as at 8, thus constituting a 90 substantially equilateral triangle. A line from one support to another does not at any point cross the center of the plate supporting the stylus-bar, thus permitting a free vibration thereof as stated.

In mounting the plate upon the base 5, I also prefer to cushion the same by means of fiber or equivalent insulating or absorbing washers 9 placed between the head of the screws 10 and the plate 6 and between 95 the plate 6 and the base 5. The stylus-bar 7 is centrally positioned between the points of support, extends through and is supported by the plate 6, the bar being cushioned by fiber washers in its contact with the plate. Thus a fiber washer 11 is positioned between 100 the shoulder or nut 12 on the stylus-bar and the plate 6, said fiber preferably extending through the plate to prevent contact of the stylus-bar with the walls of the plate. A 105 second fiber washer 13 is positioned between the plate 6 and the nut 14 which maintains the stylus-bar upon the plate. The needle is inserted at the central opening 15 and is maintained in position by the thumb-screw 16 in the usual manner. The engagement 110 of the upper end of the stylus-bar 7

- with the diaphragm 3 may be in any preferred manner. As shown, the end of the stylus-bar is enlarged as at 17 to form a shoulder on one side with a screw 18 extending through the diaphragm and a nut 19 on the opposite side. The stylus-bar, however, may be secured to the diaphragm by means of the usual cement or waxed connections, if preferred.
- 10 In the preferred form the back 2 is secured to the frame 1 in such manner as to require only a single screw 20 in connecting the parts. This is accomplished by forming a groove as at 21 in the base 5 in which the lower end of the back 2 is positioned while the upper end snugly fitting within the concentric indentation in the frame for that purpose, is secured in position by a single screw 20, as stated. This form of connection permits the ready disengagement of the back for any purpose.

In the form shown in Fig. 6, the plate is supported by five extending arms as shown. Again a line drawn from one point of connection to another does not extend through the central opening of the plate, permitting a greater degree of resiliency than if the arms 22 extended diametrically opposite one another. The arm is supported at the center 25 to freely vibrate with but limited restrictions, owing to the method of support.

In practical use the device has been found to be extremely sensitive and very satisfactory in its operation both with the hill-and-dale and with the lateral cut records. It is obvious that after having thus described my invention, various immaterial modifications may be made without departing from the spirit of my invention, hence I do not 35 wish to be understood as limiting myself to the exact form or construction set forth.

What I claim as new and desire to secure by Letters Patent is:

1. In a phonograph reproducer, a frame 45 provided with a base, a diaphragm carried by the frame, in combination with a resilient plate supported on the base at three or more points so arranged that a line passing from one point to another point will not pass through the center of the plate to permit free vibration of the edges of the plate, a stylus-bar centrally supported by the plate with relation to the points of support, with one end extended and engaged 50 with the diaphragm.

2. In a phonograph reproducer, a frame provided with a base, and a diaphragm carried by the frame, in combination with a resilient plate mounted on the base, supported at three points thereon arranged in triangular position, the margin of the plate

between contiguous points inclining inward toward the center to permit free vibration of the intermediate edges of the plate, and a stylus-bar centrally supported by the plate with one end extended and engaged with the diaphragm.

3. In a phonograph reproducer, a frame provided with a base, and a diaphragm carried by the frame, in combination with a resilient plate supported on the base at an odd number of points regularly spaced from one another, the margin of the plate between contiguous points being inclined inward toward the center, and a stylus-bar centrally supported by the plate with an end extended and engaged with the diaphragm.

4. In a phonograph reproducer, a frame having a base, and a diaphragm carried thereby, a plate adapted to be secured to the base, said plate having a central portion, and a plurality of relatively resilient arms radiating from said central portion at a plurality of points around said central portion and adapted to be secured to the base to permit said plate to freely vibrate, and a stylus-bar supported by the body portion of said plate adapted to vibrate therewith, and having one end connected with the diaphragm.

5. In a phonograph reproducer, a frame having a base, a diaphragm carried thereby, a resilient plate adapted to be secured to the base, said plate having a plurality of separated arms extending radially from the body thereof and connected near their ends with the base to permit a free vibration of the plate, and a stylus bar passing through the body portion and supported thereby, adapted to vibrate with the plate, one end of the stylus bar being connected with the diaphragm.

6. In a phonograph reproducer, a frame having a base, a diaphragm carried thereby, a plate adapted to be secured to said base, said plate having a central portion with a plurality of resilient arms extending radially from different points of the circumference of said central portion and adapted to be secured to the base to permit said plate to vibrate freely, and a stylus bar supported by the body portion of the plate adapted to vibrate therewith and having one end connected with the diaphragm.

In testimony whereof, I have hereunto signed my name in the presence of two subscribing witnesses.

ORLANDO R. MARSH.
